UNITED STATES PATENT OFFICE.

AUGUST FISCHER, OF CHICAGO, ILLINOIS, ASSIGNOR OF ONE-HALF TO
JOHANN G. EGGLERS, OF SAME PLACE.

CAR-BRAKE.

SPECIFICATION forming part of Letters Patent No. 540,829, dated June 11, 1895.

Application filed February 26, 1895. Serial No. 539,773. (No model.)

To all whom it may concern:

Be it known that I, AUGUST FISCHER, a citizen of the United States, residing at Chicago, in the county of Cook and State of Illinois, 5 have invented a new and useful Improvement in Car-Brakes, of which the following is a specification.

The object of my invention is to provide an improved construction of brake-mechanism 10 operative by wedging the brakes against the wheels of a car.

My invention consists in the general construction of my improved brake-mechanism; and it also consists in details of construction 15 and combinations of parts, all as hereinafter described and pointed out in the claims.

Referring to the accompanying drawings, Figure 1 is a bottom plan view of a car provided with my improved brake mechanism; 20 Fig. 2, a section taken at the line 2 on Fig. 1 and viewed in the direction of the arrow, and Fig. 3 a section taken at the line 3 on Fig. 1 and viewed in the direction of the arrow.

A and A' denote the two pairs of wheels of 25 a car (street-car) shown as journaled to rotate on stationary axles B secured to the bottom C of the car and projecting through the car-floor on which they are covered by caps r.

D and D' are yoke-shaped brake-beams, 30 each loosely supported in guide-clips q, q' and q² depending from the bottom of the car to engage the beams at their centers and toward their extremities, at which they carry brake-shoes D² coincident with the treads of the car-wheels, the backs of the yoke-shaped brake-beams opposing each other at opposite sides 35 of the transverse center of the car-bottom.

E and E' are yoke-shaped brake-beams supported, below the plane of the beams D and 40 D', to extend across both axles B respectively at the inner sides of the side-pairs A and A' of the wheels, each beam having at its opposite ends the longer extension E² and the shorter extension E³ beyond and parallel with the adjacent axle. The space between the adjacent 45 ends of each pair of said extensions is shown in the form of an outwardly tapering socket p. The beams E and E' are loosely supported at their extensions on guide-clips o depending 50 from the bottom of the car, near their ends on the yokes n depending from the car-bottom, and across their opposing back-ports m' by

a yoke-bar m fastened to the bottom of the car to extend transversely across it at its center; and near the junction of each beam with its 55 right-angle extension, and adjacent to the inner face of each wheel, the beam carries a brake-shoe E⁴.

F is a vertical pivot-pin having its bearings at its opposite ends, respectively, in the car-bottom and the yoke-bar m centrally between the opposing backs of the beams D, D' and those of the beams E, E'. The pin F forms the center of two horizontally rotary wedge-bars G and H, connected to cause the 65 turning of one to turn both, the former bearing on its opposite ends against the opposing backs of the brake-beams D and D', and the latter bearing at its opposite ends against the opposing backs of the side brake-beams E and E'. 70

As will be seen, by turning the bar G on its pivot in one direction it becomes wedged between the opposing backs of the beams D and D' and forces them apart to apply the brake-shoes D² with great pressure against 75 the wheel-treads; and as the bar H turns with the bar G, it becomes wedged between the opposing backs of the brake-beams E and E', forcing them apart to apply the brake-shoes E⁴ to the inner sides of the wheels. 80

As the means for operating the brake-mechanism, I show a brake-rod I pivotally connected with the bar H to one side of its center and extending thence toward one end of the car, and a brake-rod I' pivotally connected 85 with the same bar H to the opposite side of its center and extending thence toward the opposite end of the car.

At its outer end each brake-rod is connected with the lower end of an operating lever K 90 fulcrumed on the car-floor and carrying a spring-dog device l to engage a segmental rack l' for holding the operating lever in any position to which it is thrown. Where the brake-rods pass through the spaces p between the 95 extremities of the brake-beam extensions, they are provided with outwardly tapering or wedge-shaped heads h and h' which, when the brake-rods are forced outward by operating either lever K, are wedged between the adjacent ends of the beam-extensions to supplement the action of the wedge-bar G in forcing the beams E and E' to apply the brake-shoes E⁴. 100

As the parts are co-operatively connected, by throwing either lever K in one direction the brakes are applied, the operation forcing both brake-rods longitudinally outward; and 5 by throwing either lever in the opposite direction the wedge-bars G and H are both turned to release the several brake-beams and force the wedge-shaped heads h and h' from between the ends of the brake-beam extensions.

While I have shown and described brake-rods and levers as the means for setting and releasing the brakes, other means may be employed without departure from my invention, 15 the essential feature of which consists in providing either or both of the wedge-bars G and H, or equivalent devices, adapted by turning, to engage and release brake-shoe carrying brake-beams to force the brake-shoes against 20 and release them from the wheels. I do not therefore limit my improvement to the exact mechanism shown and described, as it may be variously modified without departure from my invention.

25 What I claim as new, and desire to secure by Letters Patent, is—

1. In combination with a car, brake-mechanism having the yoke-shaped brake-beams carrying brake-shoes adjacent to the inner 30 surfaces of the car-wheels, a rotary wedge-bar extending between said brake-beams, and means for turning said bar to wedge it between said brake-beams, substantially as and for the purpose set forth.

35 2. In combination with a car, brake-mechanism having the yoke-shaped brake-beams E and E' carrying brake-shoes and provided with the extensions E² and E³ affording spaces

p between their extremities, a rotary wedge-bar H extending between said brake-beams, 40 brake-rods I and I' connected with said wedge-bar near its opposite ends and having wedge-shaped heads h and h' at said spaces p, and means for actuating the brake-rods, substantially as and for the purpose set forth. 45

3. In combination with a car, brake-mechanism comprising the pairs of brake-beams D, D' and E, E' carrying brake-shoes to engage the car-wheels respectively at their treads and inner surfaces, rotary connected 50 wedge-bars G and H extending, respectively, between the beams D, D' and the beams E, E', and means for turning said bars to wedge them between their respective brake-beams, substantially as and for the purpose set forth. 55

4. In combination with a car, brake-mechanism comprising the pairs of yoke-shaped brake-beams D, D' and E, E', carrying brake-shoes to engage the car-wheels respectively at their treads and inner surfaces, wedge-bars 60 G and H connected to turn together on a common pivot-pin F and extending, respectively, between the beams D, D' and the beams E, E'; extensions E² and E³ of the beams E, E', forming between their extremities the spaces 65 p, brake-rods I and I' connected with the bar H near its opposite ends and provided with wedge-shaped heads h and h' where they pass through said spaces, and means for actuating the brake-rods, substantially as and for the 70 purpose set forth.

AUGUST FISCHER.
